DESIGN FOR A RUBBER HEEL

Ray E. Sannar, Leonard P. Tufford, and Arthur
G. Smith, Elyria, Ohio

Application February 13, 1939, Serial No. 82,942

Term of patent 14 years

To all whom it may concern:

Be it known that we, Ray E. Sannar, Leonard P. Tufford, and Arthur G. Smith, all citizens of the United States and all residents of Elyria, in the county of Lorain and State of Ohio, have invented a new, original, and ornamental Design for a Rubber Heel, of which the following is a specification, reference being had to the accompanying drawing, forming a part thereof.

Figure 1 of the drawing is a plan view of a rubber heel showing our design; and
Figure 2 is a side elevational view thereof.

We claim:

The ornamental design for a rubber heel, substantially as shown.

RAY E. SANNAR.
LEONARD P. TUFFORD.
